UNITED STATES PATENT OFFICE.

WALTER M. CHASE, OF LOS ANGELES, CALIFORNIA.

GOLF PRACTICE DEVICE AND GAME.

Application filed May 19, 1926. Serial No. 110,124.

My invention is a golf practice device and game, for practicing golf strokes and maintaining a score.

An object of my invention is a practice device against which golf balls may be struck, the said device causing a registering, indicating approximately the distance of travel of the ball and having a series of cards, strips or the like for indicating the 10 yardage from the different tees to the different holes of the golf course so that a score can be kept of the game.

A further object of my invention is to have a series of strips or cards, there being 15 one for each fairway of the course, so that a full course either of nine or eighteen holes may be played, the players keeping track of the strokes required.

In constructing my invention I utilize a 20 swinging curtain mounted on a frame, this curtain being suitably suspended so that when struck by a golf ball the curtain swings backwardly and in so doing actuates a train of gears which shifts a device having one of 25 the strips indicating the fairway of a golf course. These strips are replaceable so that after the players have holed out they may start on the subsequent fairways of the course.

30 My invention will be more readily understood from the following description and drawings, in which;

Figure 1 is a perspective view of my practice device installed in a suitable room, indicating part of the floor to be utilized as a green;

Fig. 2 is a front elevation of the device partly broken away, showing the green;

Fig. 3 is a vertical transverse section on 40 the line 3—3 of Fig. 2, in the direction of the arrows;

Fig. 4 is a horizontal transverse section on the line 4—4 of Fig. 3, in the direction of the arrows.

45 Fig. 5 is a face view of one of the strips showing one type of marking which may be utilized in the game.

In Fig. 1, the walls of a room are indicated by the numerals 1, 2 and 3, these walls preferably being suitably padded to catch missed strokes at the ball. A stand designated generally by the numeral 3 has a standard 4 with registering mechanism thereon, a simple supporting standard 5 and a cross

shaft 6 between said standards. A curtain 55 7 is mounted on a suitable frame connected to the shaft 6 so that when the curtain is struck by a golf ball which the player has hit, the curtain will swing backwardly. A stop 8 is utilized to prevent the forward 60 swing of the curtain.

The registering mechanism is substantially as follows:

A ratchet gear 9 is loosely mounted on the shaft 6 within the gear box 10 at the top of 65 the standard 4 and an arm 11 extending upwardly from the shaft has a spring pressed pawl 12 to engage the teeth of the ratchet gear and to partly rotate said gear on each backward swing of the curtain 7. On the 70 forward swing of the curtain the pawl slides over the ratchet teeth. A driving gear 13 is rigidly connected to the ratchet gear 9 and drives a pinion 14 mounted on a suitable transverse shaft. This pinion meshes with 75 a rack 15, the rack being slidable in the standard 4 and having an exposed face on which a strip or card 16 may be secured by thumb screws 17 or the like. The crank 18 is attached to the gears so that these may 80 be turned backwardly to move the rack 15 from its upper to its lower position in order to start a new game.

In starting a game the ball would be placed on a tee and struck by the player and 85 the ball striking the curtain will swing this a greater or lesser extent backwardly in accordance with the force of the blow. The strips or the like are preferably marked with a device indicating a tee, this forming a zero 90 marking and being marked in yards with a designation thereon indicating the green.

The play is continued, that is each player strikes the ball from a suitable mat or the like until the rack has been elevated to such 95 an extent that the strip indicates that the ball is on the green. The player would then place the ball on the part of the floor indicated as the green and would endeavor to put same into a suitable hole. The player 100 would keep score of strokes required from the tee until the ball is holed. If playing in competition the next player would follow the same procedure and the players could thereby compare their playing ability. 105

It will be noted that with my device the gearing may be such as to closely simulate the distance which a ball would actually

travel on a golf course. This would be ascertained experimentally by the manufacturer and the gearing such that with certain backward swings of the curtain a certain yardage would be recorded.

It is thus manifest that as the distance between holes of different golf courses varies in length, that the strips with the yardage marked thereon would be of different lengths. It is hence necessary to have the rack of such length as to accommodate the longest fairway which is apt to be found in actual golf courses.

It is thus apparent that my practice device and game is suitable for country clubs, golf clubs and the like and that each club may have a set of strips made which correspond to their different fairways. The player can thus estimate the number of strokes it takes to complete the whole course.

It will be noted that my registering device operates in an additive manner, that is, when one golf ball strikes the panel-like curtain the strip is moved upwardly, registering the number of yards the ball would have travelled and stays in such position. The second strike of the ball also adds a successive distance to the register, and so on until the whole fairway of a golf course has been covered. The player incidentally is also informed as to how far short or over the "hole" his last stroke goes.

It is manifest that the general construction and specific details of my device may be considerably changed to adapt same to different installations and manner of using. Such changes however, would be within the spirit of my invention as set forth in the description, drawings and claims.

As indicated in Fig. 5, the strip 16 is provided with certain indicia, indicating features of a golf course, for instance, the word "tee" designated by the numeral 20 indicated the tee or the zero marking. The numerals 21 indicate distance preferably in yardage. The green is designated by the word "green" or by other suitable indicating as by painting the strip a green color as indicated by the numeral 23 and if desired a hole 24 may be indicated by a round circle on the green.

Having described my invention, what I claim is:

1. A golf practice device comprising in combination a movable curtain mounted to be shifted when struck by a golf ball, and means actuated by the curtain to give an indication of some effect of the ball, said means being vertically movable to additively indicate such effects.

2. A golf practice device comprising in combination a movable curtain mounted to be shifted when struck by a golf ball, and means actuated by the curtain to indicate the distance a golf ball would travel if not

intercepted by the curtain, said means being vertically movable to additively indicate such distances of successive balls.

3. A golf practice device comprising in combination a pivoted panel like curtain to be struck by a traveling golf ball, a registering device disconnected from a ball, said registering device having a vertical movement and additively indicating the distance of successive balls.

4. A golf practice device comprising in combination a pivoted panel like curtain to be struck by a traveling golf ball, a registering device disconnected from a ball to indicate distances of a golf course, said registering device having a vertical movement and additively indicating the distance of successive balls on a golf course.

5. A golf exercising device comprising a vertical pivoted panel-like curtain, a registering device having a movable strip operated thereby, said strip indicating the distance of the golf course.

6. A golf exerciser comprising in combination a pivotally mounted panel-like curtain, a registering device operated thereby, said registering device having replaceable strips, said strips indicating different parts of a golf course.

7. A golf exercising device comprising in combination a pivotally mounted panel-like curtain, a slidable strip operated by the movement of the curtain to slide same longitudinally, the strip having means to indicate distances in a prescribed part of a golf course.

8. A golf exerciser comprising in combination a pivotally mounted panel-like curtain, a slidable rack, a system of gearing operatively connected between the panel and the rack, to move the rack longitudinally on the swinging movement of the curtain, and an indicating strip operatively connected to the rack, said strip indicating features of a golf course.

9. A golf exerciser comprising in combination a suitable stand having a transverse shaft, a panel-like curtain suspended therefrom, a slidable rack mounted in the stand, a system of gearing operatively connected between the shaft and the rack, to slide the rack on the partial rotary movement of the shaft, and an indicating strip attached to the rack, said strip indicating different features of a golf course.

10. A golf practice device comprising a stand having a pair of standards, a horizontal shaft journaled in said standards, a panel-like curtain depending from and attached to the shaft, a ratchet rotatably mounted, a pawl operatively connected to the shaft, to actuate the ratchet in one direction of swinging movement of the curtain, a slideable rack, a system of gearing operatively connected between the ratchet and the rack,

and an indicating strip attached to the rack to indicate distance in part of a golf course.

11. A golf practice device comprising a stand having a pair of standards, a horizontal shaft journaled therein, a panel-like curtain secured to the shaft and depending downwardly therefrom, an arm having a pawl attached to the shaft, a ratchet wheel rotatably mounted, positioned to be engaged by the said pawl, a gear connected to said ratchet, a pinion meshing with said gear, a rack slidably mounted among the standards, meshing with the said pinion, and indicating strips on the rack to indicate distances in a golf course.

12. In a golf practice device, an indicating strip formed of sheet material, having indicia thereon to indicate features of a golf course and means to attach said strip vertically to a device registering the impact of a golf ball.

13. In a golf practice device, a strip formed of sheet material having indicia thereon indicating the tee of a golf course

and the distance of a fairway in lineal measurement and means to attach said strip vertically to a device registering the impact of a golf ball. 25

14. In a golf practice device, an elongated strip of sheet metal having indicia thereon of different features of a golf course embodying an indicator representing a tee or zero point, an indicator representing a green and intermediate lineal measurements of distance and means to attach said strip vertically to a device registering the impact of a golf ball. 30 35

15. In a golf practice device, an indicating strip of suitable material having indicia relative to a golf course including indicators of the tee, of the green, of a hole in the green and of the intermediate lineal distance between the tee and the hole and means to attach said strip vertically to a device registering the impact of a golf ball. 40 45

In testimony whereof I have signed my name to this specification.

WALTER M. CHASE.
